TENSION FOR SHUTTLES

Elbridge R. Holmes, Worcester, Mass., assignor
to Crompton & Knowles Loom Works, Worcester, Mass., a corporation of Massachusetts

Application November 26, 1942, Serial No. 466,986

8 Claims. (Cl. 139—200)

This invention relates to tensions for loom shuttles and it is the general object of the invention to provide a simple and efficient tension which will present a smooth and uninterrupted surface to the weft and at the same time be readily assembled.

Shuttles used in narrow ware looms customarily carry a rotatable quill from which the weft is unwound as it leads to a delivery eye. In order to prevent the delivery of excess weft rotation of the quill must be stopped at the end of each stroke of the shuttle. This result has been accomplished in the past by the use of a friction device held resiliently against the mass of yarn on the quill but those mechanisms of this type which have operated satisfactorily have required several steps in their application to the carrier arm and have not been either readily assembled or removed. It is an important object of my present invention to provide a friction pad which can be conveniently and quickly attached to its carrier arm.

As the quill rotates it tends to move the pad laterally with respect to the carrier arm and it is another object of my present invention to form the pad with two parts spaced laterally to provide room to receive a carrier arm but placed to prevent substantial movement of the pad laterally of the arm.

It is a further object of my present invention to provide a tension pad formed of a single piece of material and provided with a bendable recessed arm which can be pressed into holding relation with respect to the carrier arm. The arm is formed integral with a plate having a smooth uninterrupted surface which will not abrade the yarn on the quill. The bendable part of the pad is on the under side of the latter and no part of the structure by which the pad is mounted on the carrier arm can engage the quill.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a front elevation of a shuttle having my invention applied thereto,

Fig. 2 is an enlarged vertical section on line 2—2, Fig. 1, showing a convenient form of resilient mounting for the carrier arm,

Fig. 3 is a plan view of the tension pad on an enlarged scale,

Fig. 4 is a front elevation of the pad looking in the direction of arrow 4, Fig. 3,

Fig. 5 is a vertical transverse section on line 5—5 of Fig. 3,

Fig. 6 is a front elevation of the pad showing the position of the holding and clamping arm before the latter is pressed into normal holding position, and

Fig. 7 is a bottom plan looking in the direction of arrow 7, Fig. 4.

Referring to the drawing, I have shown the usual type of bow shuttle S having a quill Q rotatably mounted on a spindle 10 which extends across the lower part of the opening 11 which receives the quill. The weft W on the quill is led from the latter to a pair of guides 12 and then to the delivery eye 13. As the shuttle moves back and forth in the loom the consumption of weft causes rotation of the quill on the spindle 10 and it is desirable that excess rotation be prevented in order that proper tension may be maintained in the weft.

The shuttle is provided with a carrier arm 20 mounted at one side of the opening 11. The mounting may include a cylinder 21 secured in the body of the shuttle and having a fixed bearing 22 for the bent end 23 of the carrier arm. The end 23 has secured thereto a collar 24 within the cylinder and is surrounded by a spring 25 the left end of which as shown in Fig. 2 enters the collar 24 while the right end enters a sleeve 26 which affords a sliding bearing for the right end of the bent part 23. The sleeve is provided with peripheral longitudinally extending grooves 27 two of which are shown in Fig. 2 to receive guide pins 28 fixed to the cylinder 21. A flange 29 on the cylinder limits outward movement of the sleeve. The spring exerts an upward force on the carrier arm or wire as viewed in Fig. 1 and this force may be varied by pressing the sleeve inwardly against the compressive action of spring 25 and turning the same to change the slots 27 which receive the pins 28.

The particular form of tension shown herein is for illustrative purposes only and any similar mechanism may be employed to urge the carrier arm toward the quill. Reference may be had to prior Patent No. 1,226,519 for a further understanding of the matter thus far described.

In carrying my present invention into effect I provide that end of the carrier arm remote from its pivotal connection with a pad designated generally at 30 and comprising preferably a body of sheet metal having a top plate 31 generally of rectangular form with rounded corners and having a smooth uninterrupted upper surface for engagement of the weft with the quill. One of

the long sides of the top plate has bent downwardly therefrom a lip 32, while one of the short sides has extending therefrom a holder foot 35 extending under the top plate. The end of foot 35 has a transverse semi-cylindrical upwardly facing recess 36 the axis of which is in alignment with the lip 32, as shown in Fig. 4, to receive the bent end 37 formed on the free end of the carrier arm.

The tension pad will be made and bent in the form shown in Fig. 6, after which the straight shank part 40 of the carrier arm 28 will be inserted between the lip 32 and the adjacent end of the foot 35 with end 37 over the recess 36, after which the foot is pressed from the position shown in Fig. 6 toward plate 31 to the position shown in Fig. 4. The end 37 is thus held against upward displacement out of the recess by the top plate and against lateral displacement by lip 32 and foot 35. The recess provides a loose fit with the bent end 37 of the carrier arm so that the pad is free to pivot vertically to insure contact of the top of plate 31 throughout its length with the weft and permit the pad to accommodate itself to the changing contours of the quill.

The pad is preferably made of a non-tarnishing material such as stainless steel and serves by its pressure on the weft to arrest excess rotation of the quill when the shuttle comes to rest in the loom. If the pad requires renewal the foot 35 may be bent downwardly sufficiently to permit removal of end 37 from the recess, after which a new pad may be placed on the carrier as already described.

From the foregoing it will be seen that I have provided a tension pad having a smooth uninterrupted weft engaging surface having formed integrally therewith the foot which may be bent into position to hold the pad on the carrier arm. It will also be seen that the lip 32 prevents lateral displacement of the pad with respect to the carrier arm in one direction while the foot 35 prevents displacement in the opposite direction, and the top plate holds bent end 37 in the recess 36.

Having thus described my invention it will be seen that changes and modifications may be made therein by those skilled in the art without departing from the spirit and scope of the invention and I do not wish to be limited to the details herein disclosed, but what I claim is:

1. In tension mechanism for a shuttle having a weft quill and a carrier arm mounted on the shuttle and tending to move toward the quill, a tension pad for the guide comprising a plate having a smooth uninterrupted surface to engage the weft on the quill, a lip depending from one side of the plate and located at one side of the carrier arm, and a foot depending from another side of the plate and located on the opposite side of the carrier arm, said foot having a recess concave toward the plate to receive the carrier arm and extending in a direction toward and from the lip, said foot and lip cooperating to limit lateral movement of the pad relatively to the carrier arm and said foot and plate cooperating to limit vertical movement of the pad relatively to the carrier arm.

2. In tension mechanism for a shuttle having a weft quill and a carrier arm mounted on the shuttle and tending to move toward the quill, a tension pad for the quill comprising a plate having a smooth uninterrupted top surface to engage the weft on the quill, a foot integral with the plate bent thereunder and having a free end.

formed with a lateral elongated recess, said carrier arm being held in the recess between said plate and said foot due to proximity of the latter to said plate, and a lip depending from said plate 5 axially aligned with the elongated recess to cooperate with said foot to limit lateral movement of the pad relatively to said carrier arm.

3. In tension mechanism for a shuttle having a weft quill and a carrier arm mounted on the shuttle and tending to move toward the quill, a tension pad for the quill comprising a plate having a smooth uninterrupted top surface to engage the weft on the quill, a foot integral with the plate and extending from one edge thereof 15 under the plate along the bottom of the latter, the free end of said foot having an elongated recess transverse of the foot to receive the carrier arm, and a lip integral with said plate and axially aligned with said recess to cooperate with 20 the foot to limit lateral movement of the pad relatively to said carrier arm.

4. In tension mechanism for a shuttle having a weft quill and a carrier arm mounted on the shuttle and tending to move toward the quill, a tension pad for the quill comprising a plate having a smooth uninterrupted top surface to engage the weft on the quill, and a foot integral with said plate and extending from one edge thereof under the plate toward the opposite edge 30 of said plate, said foot having a transversely recessed part concave to the bottom of the plate located intermediate said edges to receive the carrier arm and provide a pivotal connection between the carrier arm and pad.

5. In tension mechanism for a shuttle having a weft quill and a carrier arm mounted on the shuttle and tending to move toward the quill, a tension pad for the quill formed of sheet metal and having a plate formed with a smooth uninterrupted top surface to engage the weft on the quill, and a foot integral with one edge of said plate and bent thereunder toward the opposite edge of the plate, said foot having the free end thereof formed with a transverse elongated recess concave to the plate to receive the carrier arm and hold the latter between the plate and foot and provide a pivotal connection between the pad and carrier arm, said free end of said foot being bendable away from the plate to permit removal of the carrier arm from the recess.

6. A quill engaging pad for the carrier arm of a loom shuttle tension, said pad comprising a plate having a smooth uninterrupted top surface to engage the quill, and a foot integral with the plate and bent thereunder and provided with a free end having a transverse recess to receive the carrier arm and locate the latter between said plate and foot, said foot being bendable away from said plate to permit removal of the carrier arm from the recess.

7. A quill engaging pad for the carrier arm of a loom shuttle tension, said pad comprising a plate having a smooth uninterrupted top surface to engage the quill, and a foot integral with said plate and bent thereunder and having a transverse recess concave to the plate to receive said carrier arm, said foot being bendable relatively to the plate to two positions with respect to said plate, the foot when in one position spaced from the plate permitting entry and removal of the carrier arm into and out of said recess by a motion transverse of the plane of the plate, and said foot when in the other position closer to the plate holding the carrier arm in said recess under the plate to prevent removal of the carrier

arm out of the recess by a motion transverse of the plane of the plate.

8. A quill engaging pad for the carrier arm of a loom shuttle tension, said pad comprising a plate having a top smooth uninterrupted weft engaging surface, a lip integral with and dependent from the plate, a foot integral with the plate

and bent to extend thereunder, the free end of said foot having a transverse elongated recess axially aligned with said lip to receive the carrier arm, said foot being bendable with respect to the plate so that said recess can be moved into and out of alignment with said lip.
